UNITED STATES PATENT OFFICE.

NICHOLAS P. HEISDORF, OF NEW YORK, N. Y.

WATERPROOF AND BUOYANT FABRIC.

1,276,909.

Specification of Letters Patent. Patented Aug. 27, 1918.

Application filed May 24, 1917. Serial No. 170,695.

To all whom it may concern:

Be it known that I, NICHOLAS P. HEISDORF, a subject of the Emperor of Germany, residing at New York, in the county of New York and State of New York, have invented certain new and useful Improvements in Waterproof and Buoyant Fabrics; and I do declare the following to be a full, clear, and exact description of the invention, such as 10 will enable others skilled in the art to which it appertains to make and use the same.

This invention relates to improvements in waterproof and buoyant fabrics adapted to be used in the manufacture of bathing 15 suits, rainproof garments, and the like.

The primary object is to provide a fabric incorporating kapok in its weave, whereby a person wearing a bathing suit made therefrom will be prevented from sinking below 20 the surface of the water.

Another object is to provide a kapok fabric which will be buoyant and waterproof and well adapted for use in the manufacture of waterproof wearing apparel now made 25 from rubber, and at the same time providing a warmer garment than that made from rubber.

With these and numerous other objects in view, my invention resides in the novel 30 features of construction and arrangement of the parts as illustrated in the accompanying drawings, and more particularly pointed out in the specification and claims.

In the accompanying drawing:

35 Figure 1 is a longitudinal section of my improved fabric showing loops of kapok depending therefrom;

Fig. 2 is a top plan view of a portion of the fabric showing kapok incorporated 40 therein;

Fig. 3 is a view similar to Fig. 1 but showing the loops of kapok cut; and

Fig. 4 is a longitudinal sectional view of 45 a fabric including the kapok tufts flattened and held in place by a suitable lining.

Similar numerals of reference are employed to indicate corresponding parts throughout the several views.

In the manufacture of my kapok fabric a base or supporting fabric 1 made up of 50 warp strands 2 and weft or woof filler strands 3 is made, and this is preferably woven or knitted quite loosely. It is to be understood that any desired material the strands of which possess a comparatively large tensile strength may be used in forming this base 1, but I preferably employ wool or worsted loosely woven, as hereinbefore stated.

Pile tufts of kapok 4 are then woven into 60 the meshes of the fabric 1 and looped over the weft threads 3, the ends of said tufts being flattened or spread out to cover the surface of the fabric and to serve as a means for retaining said tufts in the meshes. The 65 kapok is woven into the base or supporting fabric 1 in the manner now to be described.

Preferably every second warp strand 5 is formed from kapok, and, in weaving, one 70 side of the base 1 is provided with a plurality of loops 6 formed from the kapok strands 5 and after a desired length of cloth is thus formed it is passed through a machine which cuts the kapok loops 6, thereby 75 forming tufts. The tufts are then flattened as hereinbefore stated and a lining cloth 7 is placed over said ends and quilted to the base 1 in any desired design so as to retain the tufts in proper position. 80

It will be readily understood that the kapok strands 4 may be woven parallel with the weft strands 3 of the base 1 as well as with the warp strands 2, or they may be woven in both directions, thereby providing 85 a greater buoyant and waterproof surface. It is to be understood that this fabric may be used without the lining 7, although it is preferable to use it with a lining.

From the foregoing description, taken in 90 connection with the accompanying drawings, the construction of my kapok fabric will be readily understood, but it is to be understood that within the scope of the appended claims numerous changes may be made without sacrificing the principal advantages.

I claim:

1. A buoyant fabric made up of an open mesh base fabric, the strands of which possess a comparatively large tensile strength 5 and kapok incorporated in the meshes thereof.

2. A buoyant fabric made up of an open mesh base fabric including warp and weft strands, kapok tufts looped around said 10 strands and having their ends spread out

on said base, and a lining to cover said ends and to be connected to said base fabric.

In testimony whereof I have hereunto set my hand in the presence of two subscribing witnesses.

NICHOLAS P. HEISDORF.
